UNITED STATES PATENT OFFICE.

ENICE JEAN LOUBET, OF NEW YORK, N. Y.

DESIGN FOR A DOLL.

Application filed March 6, 1923. Serial No. 5,379. Term of patent 3½ years.

To all whom it may concern:

Be it known that I, ENICE JEAN LOUBET, a citizen of France, and a resident of the city of New York, borough of Manhattan, in the county and State of New York, United States of America, have invented a new, original, and ornamental Design for a Doll, of which the following is a specification, reference being had to the accompanying drawings, in which the figure is a face view of a doll constituting my new design.

I claim:

The ornamental design for a doll, as shown.

ENICE JEAN LOUBET.
